ENGLAND

OSCILLATING ELECTRIC FAN

Application filed February 12, 1927. Serial No. 167,808.

Our invention has reference to oscillating fans of the type in which, in order to provide for an orbital travel or simultaneous displacement of the fan-wheel or propeller in two directions, the displaceable unit constituted by the motor-casing and fan-wheel is so pivotally mounted in relation to the fixed base or support as to be capable of swinging in two intersecting planes and the fan-motor 10 shaft is adapted to drive, through a reduction gearing, a slow-motion shaft which co-operates with an intermediate traversing mechanism to realize the orbital movement.

According to our said invention, the traversing mechanism is constituted by a link which is connected to and rotates with the motor-driven slow-motion shaft and is also anchored (preferably by a ball or universal joint) to a fulcrum that is fixed in relation 20 to the non-displaceable unit.

According to one application of the invention, as illustrated in Figures 1 to 5 of the accompanying drawings, the anchored link is hinged to the slow-motion shaft in such a 25 manner that whilst the former is constrained to turn crankwise with the latter, it is also capable of simultaneously changing its angularity with respect to the slow-motion shaft.

Figure 1 is a sectional elevation of the 30 fan showing the general arrangement of a hinged-link mechanism and also exemplifying, in full and dotted lines respectively, the two extremes of the oscillating movement of the displaceable unit upon the horizontal 35 trunnions A.

Figure 2 is a sectional plan (the section being taken on the dotted lines 2—2, Figure 1) similarly showing the two extremes of the movement of the displaceable unit upon the 40 vertical trunnion B.

Figures 3 and 4 are sections of the mechanism taken respectively on the dotted lines 3—3 and 4—4, Figure 1.

Figure 5 is a section of a modification.

Figure 6 shows another modification in which the link is fixed to the slow-motion shaft.

In the construction illustrated, the motor-casing *a* is mounted upon horizontal trunnions A in a forked support *a*² which in turn

is connected by a vertical trunnion B to the pedestal *a*⁴.

The fan-motor shaft *b* is extended rearwardly through a bearing *b*¹ attached to the casing *a* into a gear box *c*, where, by a worm *b*² and worm-wheel *b*³, it drives a shaft *b*⁴ and the latter, by another worm *b*⁵ and worm-wheel *b*⁶, transmits the reduced drive to a slow-motion shaft *d*, which, for the sake of compactness and convenience in manufacture, 55 is positioned below and in parallel relationship to the motor-shaft *b*.

Rigidly attached to the base *a*⁴ is a bracket *e* which extends into the space provided between the back of the motor-casing and the reduction gear-box and supports a ball-ended fulcrum-piece *f*, whilst between this fixed fulcrum *f* and the forward end of the slow-motion shaft there is interposed a rigid link *g*, whose one extremity is connected with the ball end *f*² of the fulcrum in a manner which provides for a universal movement of the said link relative to the fulcrum, whilst the other extremity *g*² is engaged in a forked part *d*² of the shaft *d* and is hinged to the latter by a pin *g*³ (see Figure 4). This construction of hinge permits of an angular displacement or rocking movement of the link 70 relatively to the shaft *d*, and also ensures that the link will rotate crankwise with the 75 said shaft when the reduction gear is driving the latter.

Such crankwise rotation of the link *g* by and with the slow-motion shaft and around the fixed anchorage *f*² results in the transmission to the displaceable unit of the fan of a lateral movement about the vertical trunnion centre B but by virtue of the hinging of its end *g*² to the shaft *d*, it follows that whilst the link is being thus carried around the fulcrum *f*, its angularity with respect to the axis of the shaft is continually so changing that it re-acts lever-wise upon the displaceable unit. That is to say, when the displaceable unit is at the limit of its upward sweep in the vertical 90 direction and the shaft *d* is below the fulcrum *f*, the link assumes an acute angle with respect to the said shaft as shown in full lines in Figure 1, but as the drive carries the rocking link around the fulcrum, the angularity 95 100

of the said link with respect to the shaft decreases until, when the link has been carried above the fulcrum, the same is inclined at an obtuse angle to the shaft between the latter and the fulcrum as indicated in dotted lines 5 in the said Figure 1. The fixed leverage point from which these changes of angularity occur being the fulcrum f , the resultant reaction upon the displaceable unit realizes the compounding with the lateral sweep upon the 10 trunnion B of a vertical oscillation upon the trunnions A which results in the orbital travel of the fan-wheel.

The dimensions of the orbit traversed by 15 the fan-wheel depends on such factors as the length of the link, the pitching of the fixed fulcrum centre in relation to the axial centre of the slow-motion shaft and (or) the disposition of the axis of the link hinge-connection 20 g^3 with respect to the axis of rotation of the shaft d , and may be varied by changing either or all of these factors. For instance, the orbit may be adjustable or variable for a given length of link by embodying in the mechanism, a screw adjustment whereby the relative positions of the elements g , d may be altered, such an adjustment being shown in 25 Figure 5 where the link g , instead of being directly hinged to the slow motion shaft, is fulcrumed on the plain-end of a screw i which is carried by and is adjustable in an extension d^6 of the shaft d .

The character of the orbit is also affected 35 by the angle which the axis of the slow-motion shaft makes with the axis of the fan spindle, and may be modified by inclining the axis of the slow-motion shaft towards the centre of oscillation on the trunnions A , or by arranging the two shafts so that both their axes 40 point to the centre of movement of oscillation.

A hand-controlled clutch (shown in Figure 4) provides for the stopping and starting of 45 the oscillating mechanism and for the locking of the displaceable fan-unit so that the fan-wheel will discharge in any desired direction as a non-oscillator. It also allows the drive from the transmission gearing to slip should the displaceable unit be obstructed by 50 any outside agency, and of the automatic restoration of the drive when the obstruction is removed.

The said clutch comprises essentially a hand-operable member o which is mounted, 55 together with a friction device o^1 , on the slow-motion shaft d in such relation to the gear-wheel b^6 (which is loose on the shaft) and to a wall c^2 of the gear box that, by the appropriate actuation of the said control member, 60 either the said gear wheel b^6 may be frictionally connected to the shaft, or the shaft may be locked in relation to the gear-box.

The part of the shaft d that extends 65 through, or registers with, an aperture in the side-wall of the gear-box is screwed at o^3 and

carries the control member o which consists of a nut that extends through the said gear-box aperture and is provided externally with a rotating knob. Internally the member is provided with a collar c^5 opposed to the inner 70 face of the wall c^2 , whilst between this collar and the loose worm wheel, the friction spring o^1 and washer o^6 are interposed; the thrust of this spring against the worm-wheel keeping the latter up to an abutment-shoulder or 75 disc on the shaft.

The thrust of the spring on the worm-wheel is regulated by adjustment of the control member, and by screwing the member inwards, the wheel may be practically locked to 80 the shaft so that the mechanism operates normally to actuate the oscillating gear although, since the locking is effected through the spring, the arrangement permits of the gear-wheel slipping on the shaft and automatically cutting out the oscillator in the event of the oscillating part of the fan being obstructed by outside agency. Also, by easing off the control-nut pressure on the friction device, the gear wheel may be allowed to run 85 idly on the shaft for stopping the oscillation mechanism whilst by screwing out the control member to the full extent until its internal collar bears against the face c^2 of the gear-box wall, the slow-motion shaft is locked 90 to the box and renders the displaceable fan-unit unmovable.

In the modified form of traversing gear shown in Figure 6, the slow-motion shaft is disposed at such an angle or inclination to 100 the fan-wheel shaft as to admit of the desired movement being obtained by a link member which is rigidly fixed to the slow-motion shaft. The hinging of the shaft end of the link is thus eliminated.

In the said Figure 6, the displaceable unit of the fan is shown, in full and dotted lines respectively, at the two extremes of its movement on the centre A , and the traversing mechanism is similarly shown in the positions 110 assumed at these extremes.

The slow-motion shaft a is housed in the part b^1 of the reduction-gear box b and is thereby definitely fixed at the angle shown to the part b^2 of the casing wherein the fan wheel shaft is housed, and the link-member d of the traversing mechanism is fixed at one end to the extremity of the shaft a , whilst its other end is connected by a ball or universal joint e to the fixed fulcrum f .

The inclined slow-motion shaft may be driven by skew gearing or by a friction drive.

Having described our invention, what we claim and desire to secure by Letters Patent is:—

1. An electric fan of the class described, comprising a base having a fulcrum thereon, and traversing mechanism including a motor-driven slow-motion shaft and a link hinged thereto to turn crankwise therewith,

the link being capable of simultaneously changing its angularity with respect to the shaft and being anchored by a universal joint to the fulcrum.

2. An electric fan of the class described, comprising a base having a fulcrum thereon, traversing mechanism including a link and a motor-driven slow-motion shaft, the link being connected to and rotating with the shaft and also being anchored to the fulcrum, and driving gear for the traversing mechanism, such gear comprising a gear-wheel loosely mounted on the shaft and a hand-controlled clutch device, the shaft being provided with means screwed thereon through which it is connected to the clutch device, such means providing for the locking of the shaft to the base for throwing the driving gear out of action.

20 In testimony whereof we have hereunto set our hands.

NEVILLE W. GILBERT.
